JULIUS H. KAESEN, OF NEW YORK, N. Y.

ELECTRIC-WIRE-TERMINAL CLIP.

1,005,846.

Specification of Letters Patent. Patented Oct. 17, 1911.

Application filed December 2, 1910. Serial No. 595,214.

To all whom it may concern:

Be it known that I, JULIUS H. KAESEN, a citizen of the United States of America, residing at New York, in the county of New York and State of New York, have invented a new and useful Electric - Wire - Terminal Clip, of which the following is a specification.

My invention relates to improvements in connecting clips or devices for the terminals of electric conductors, and more particularly to devices which are utilized for the purpose of connecting electric conductors with spark-plugs in internal combustion-engines of the ordinary type, although the application of said invention is not limited to spark-plugs but is quite general in its scope.

This invention consists essentially of an internally screw-threaded sleeve, and an externally screw-threaded member in such sleeve, which interior member is provided at one terminal with certain peculiar means for attaching the electric conductor thereto, and at the other terminal with certain peculiar means for securing the device to a wire, binding-post, central electrode, or other member with which electrical connection is desired, such last-mentioned means being operated by said sleeve when actuated on said interior member through the medium of the screw-threads, all as hereinafter set forth.

The objects of my invention are, first, to produce a simple, durable and comparatively inexpensive device for attaching an electric conductor to and detaching it from the central electrode of a spark-plug or to the binding-post of a telegraph, telephone, or other electrical instrument or apparatus, such conductor being permanently attached to said device; second, to provide in such a device for absolute electrical connections at both ends, or with the electric conductor and with the central electrode or other corresponding member, thus insuring against loose and imperfect connections and accidental detachment, and obviating the annoyance caused thereby, and, third, to provide a device of this kind that can be easily and quickly operated or manipulated for attachment to or detachment from the member with which it is used as a connecting medium for the conductor or wire.

Other objects will appear in the course of the following description.

I attain these objects by the means illustrated in the accompanying drawings, in which—

Figure 1 is a side elevation of a clip which embodies a practical form of my invention, the same having an electric conductor secured thereto and being itself attached to a spark-plug; Fig. 2, a fragmentary view of parts of said clip and of a slightly different spark-plug, the two being connected as in the preceding view; Fig. 3, an interior view of the clip, the sleeve being in section; Fig. 4, an interior view of the clip taken at right-angles to the preceding view, the sleeve and parts of the internal, threaded member being in section, and the conductor being omitted; Fig. 5, a cross-section on lines 5—5, looking in the direction of the associated arrow, in Fig. 4; Fig. 6, a rear or inner end elevation of said internal, threaded member; Fig. 7, an interior view of a modified form of clip, the sleeve being in section, and, Fig. 8, a similar view taken at right-angles to Fig. 7.

Similar figures refer to similar parts throughout the several views.

In each of Figs. 1 and 3 a short piece of an electric conductor appears at 1 and its insulation at 2.

As already noted, my improved terminal or connecting clip, although it may be used in connection with electrical apparatus in general, is especially designed for use in connection with spark-plugs of internal-combustion engines, hence by way of illustration said clip is represented in each of two cases as being applied to a spark-plug. Only the upper portion of a spark-plug is shown in each case, such portion consisting, in Fig. 1, of a fragment of an insulator 3 and of a central electrode 4 therein, a cap 5 on such insulator, and a clamping-nut 7 threaded to the upper protruding terminal of such electrode, and, in Fig. 2, of the insulator and electrode, as before, and a cap 8 which has a headed binding-post 9 at the top.

Giving attention now to the clip itself, it may be observed first that the same comprises an internally screw-threaded sleeve 10, usually although not imperatively necessary of fibrous or other suitable insulating material, an externally screw-threaded member or body 11 in said sleeve with its screw-threads in engagement with the sleeve

screw-threads, a fastener 12 at the inner end of said body for the conductor 1, and a pair of gripping or clamping members or jaws 13 at the outer terminal of said body, 5 said jaws being adapted to engage or release a spark-plug terminal member, such as the central electrode 4 between the cap 5 and the clamping-nut 7, as in Fig. 1, or the headed binding-post 9, as in Fig. 2, or 10 a binding-post or equivalent terminal member of some other electrical device, accordingly as the sleeve is screwed in the direction to advance it or in the direction to retract it. The body 11 and its parts or members, including the fastener 12 and the jaws 13, are made of metal which is a good conductor of electricity.

Preferably the sleeve 10 is screw-threaded throughout its entire length, so that the 20 body 11 can be introduced at either end. The interior diameter of the sleeve 10 is of a size which will permit said sleeve to be slipped over the insulation 2.

For the body 11 I prefer to employ a 25 member having flat sides and screw-threaded edges, substantially as shown in the drawings, which fits the sleeve 10 and can be screwed in or out of such sleeve or enables the latter to be screwed in either 30 direction thereon.

The form of fastener 12, represented in Figs. 3, 4, 5 and 6, consists of a strip 14 riveted at 15 to one side of the member or body 11, and extending beyond the inner 35 end of said body to be bent over or doubled upon itself to produce, with a screw 16, the fastener proper. The screw 16 passes through the lip of the fastener 12 and is tapped into the main stem portion of said 40 fastener. The exposed end of the conductor 1 is received in the loop at the inner terminal of the strip 14, and is securely clamped therein by means of the screw 16. In practice, the sleeve 10 is first placed on 45 the insulation 2, then while the screw 16 is loose the terminal of the conductor 1 which has been freed from said insulation is passed through the aforesaid loop and said screw is tightened, and finally said sleeve 50 is slipped forward and screwed on to the body 11. In this manner and by this means the clip is securely attached to the conductor and the joint between them is hidden. Although the connection between the 55 conductor 1 and the clip is of a permanent nature and may be permanent, nevertheless, the parts can be easily and quickly disconnected, if for any reason disconnection be desired, by unscrewing the sleeve from 60 the body and sliding said sleeve along on the insulation away from said body, loosening the screw 16, and withdrawing said conductor from the loop of the fastener 12. The loop of the strip 14 is notched at its 65 inner end, as indicated at 17, to afford a

better fastening member and bearing for the conductor.

The jaws 13, in the construction shown in Figs. 1, 2, 3, 4 and 5, are flat, they lie in the same plane, and their interior or adjacent edges, near the outer ends of said jaws, are notched, indented or recessed, as represented at 18, to enable the jaws when closed not only to grasp firmly an object between them, such as the electrode 4 or the binding-post 9, but also to insure a good electrical contact. The inner terminal portions or shanks of these jaws are received in a central slot 19 in the body 11, which slot opens through the edges and the outer end of said body, and the inner ends of said shanks are pivoted at 20 to the body. The outer edges of the jaws 13 are curved outwardly, adjacent to the front end of the body 11 and consequently to the corresponding end or edge of the sleeve 10, to form cam edges or surfaces 21-21. Said cam surfaces receive the thrust from the sleeve 10 when it is advanced, or from an interposed follower 22, with the result that the 70 jaws swinging on their pivots 20 are forced closer and closer together as said sleeve advances. In this way the jaws are closed tightly upon a spark-plug or other terminal, and they are released from such terminal 75 by retracting the sleeve and thus permitting 80 said jaws to separate or open.

The follower 22 may be merely a disk of sufficient diameter to cover the front end of the sleeve 10, and slotted at 23 to receive 85 the shanks of the jaws 13. This follower acts directly on the cam surfaces 21 of the flat jaws and so relieves the sleeve from such action or from direct contact with said surfaces, wherefore said sleeve is protected 90 from wear and the jaws are operated with greater facility; moreover, the follower serves as a closure for the front end of the sleeve, and so prevents dirt, dust, and other 95 foreign substances from getting into the 100 same, and enhances the appearance of the clip. Nevertheless, the flat jaws may be used quite successfully without the follower.

The pivots 20 are inserted in the body 11 and extend across the slot 19 in such body 115 and through the shanks of the jaws 13 in such slot.

The clip that appears in Figs. 7 and 8 is slightly cheaper perhaps than the other, although the construction of the former is not 120 radically different from that of the latter. A resilient metallic strip 24 is here used, such strip being bent double and receiving 125 between its major or body portions the member 11. The aforesaid body portions of the strip 24 are riveted to the member 11 at 25. The middle part of the strip 24 is looped and provided with a screw 16 to form the fastener 12 at the inner end of the member 11, and the outer terminals of said strip 130

are bent into suitable shape to form the jaws 13 with their cam surfaces 21. The jaws in this instance do not differ greatly in shape from those in the first instance, but inasmuch as their cam surfaces 21 are wider, immediately adjacent to the slotted end of the body 11 at least, ample bearing surfaces are afforded for the contiguous edge of the sleeve 10, and the follower need not be used in connection therewith.

The conductor is attached to the clip shown in the last two views in the same manner as has already been explained in connection with the clip shown in the other views, and the jaws of the Figs. 7 and 8 clip are closed by advancing the sleeve and opened or permitted to open by retracting the sleeve, the operation being practically the same as before, only in the last illustrated example the jaws being resilient open themselves when released by the sleeve, while in the other examples the jaws do not so open. The functional difference just pointed out between the resilient and non-resilient jaws is not of particular moment.

I am aware that various other changes and modifications in the shape, size, and construction of some or all of the parts of my clip, besides those herein shown and described, such as will occur to others skilled in the art to which said clip belongs, may be made without departing from the nature of my invention, wherefore I desire to include all such changes and modifications and to cover them by my claims.

What I claim as my invention, and desire to secure by Letters Patent, is

1. An electric-wire terminal clip comprising a sleeve open at both ends, and a member in said sleeve in threaded engagement therewith, such interior member being provided at one terminal with a fastener for an electric conductor, and at the other terminal with protruding gripping members having parts which extend beyond the adjacent edge of said sleeve, so that said gripping members are actuated toward each other

when said sleeve is advanced on said interior member.

2. The combination, in an electric-wire terminal clip, with an exterior sleeve, of an interior member in threaded engagement with said sleeve, such interior member being provided at one terminal with a fastener for an electric conductor, and at the other terminal with gripping members having cam surfaces and arranged and adapted to be actuated toward each other when said sleeve is advanced on said interior member.

3. The combination, in an electric-wire terminal clip, with an exterior sleeve, of an interior member in threaded engagement with said sleeve and provided at its outer terminal with gripping members, and at its inner terminal with a loop and a screw arranged to secure an electric conductor to the adjacent end of said interior member.

4. The combination, in an electric-wire terminal clip, with an exterior sleeve, of an interior member in threaded engagement with said sleeve and provided at its inner terminal with a fastener for an electric conductor, and a pair of gripping members, having cam surfaces, pivotally attached to said plug at its outer terminal and arranged and adapted to be actuated toward each other when said sleeve is advanced on said interior member.

5. The combination, in an electric-wire terminal clip, of an exterior sleeve, an interior member in threaded engagement with said sleeve, a loop and a screw at the inner terminal of said interior member to form a fastener for an electric conductor, and a pair of gripping members, having cam surfaces, pivotally attached to said interior member and adapted to be actuated toward each other when said sleeve is advanced on said interior member.

JULIUS H. KAESEN.
